DIRECT READING SPEED CALIPER

Harry B. Lehman and Manuel F. Arias,
Miami, Fla.

Application May 5, 1934, Serial No. 724,185

4 Claims. (Cl. 33—166)

This invention relates to measuring instruments and particularly to calipers.

The general object of this invention is to provide an instrument of this character which is particularly adapted for the use of ordinary mechanics, unskilled in the use of micrometers and such instruments of extreme precision. Such instruments reading in thousands of an inch or in millimeters must be "translated" by the ordinary mechanic into terms he is familiar with and constantly uses. Such an ordinary mechanic is perfectly familiar with and constantly uses fractions of an inch, as one-sixteenth, one thirty-second, one sixty-fourth, etc., but he cannot readily, if at all, translate thousandths of an inch into these terms and hence more particularly it is our object to provide a caliper which, while capable of approximate measurements of one-thousandth of an inch, if necessary, is based upon the use of the ordinary units of measurements as one-half, one-fourth, one-eighth or one sixty-fourth of an inch.

A further object is to provide an instrument of this character which may be very rapidly and easily read and used, particularly by mechanics having no, or very little, knowledge of the use of micrometers.

A further object in this connection is to provide a caliper in which the units of one-sixteenth of an inch or the multiples thereof are read by a vertical series of graduations on the fixed barrel and in which fractions of said units (as one thirty-second or five thirty-seconds, for instance, or one sixty-fourth or eleven sixty-fourths, for instance) are read through an aperture on the fixed barrel and by reference to a longitudinal series of graduations on the spindle of the instrument and with reference to the graduations on the rotatable barrel, the numbers on the spindle giving the numerator of the fraction, the numbers on the rotatable barrel giving the denominator.

Other objects will appear in the course of the following description.

Our invention is illustrated in the accompanying drawing, wherein:

Figure 1 is an elevation of a caliper constructed in accordance with our invention;

Figure 2 is a longitudinal sectional view thereof;

Figure 3 is an elevation of the fixed barrel showing the scale used thereon;

Figure 4 is a projection of a portion of the rotatable barrel, showing the graduations thereon;

Figure 5 is a projection or flattened out view

of a portion of the surface of the spindle showing the graduations thereon.

Referring to the drawing, 10 designates the yoke or frame of the caliper having at one end the anvil 11 which is screw-threaded into the terminal end 12 of the frame so that it may be adjusted to take up wear and compensate for inaccuracies and which is adapted to be held in set position by means of a screw 13. The opposite end of the frame is formed with the collar 14 and disposed within this collar and held thereby against rotation is a fixed barrel 15. This barrel projects below the collar 14 and is there reduced in diameter as at 16 and formed with the sight aperture 17. The barrel 15 extends upward above the upper end of the frame and disposed within this barrel is the internally screw-threaded element 18, the upper end of this element projecting out slightly beyond the upper end of the barrel and being split so that a nut 19 may be engaged therewith whereby the element 18 may be contracted from time to time to take up wear. Any other means for this purpose may be used, however. This element 18 is internally threaded as at 20, these threads having a pitch of sixteen to the inch.

Coacting with the fixed barrel 15 is the rotatable barrel 21 which fits snugly over the fixed barrel and which carries within it the spindle 22, that portion of the spindle disposed within the barrel 21 being threaded as at 23, these threads having the same pitch as the threads 20. Thus, it will be seen that a complete rotation of the barrel 21 upon the barrel 15 will move the barrel 21 and the spindle 22 a distance of one-sixteenth of an inch.

The barrel 21 is slightly beveled at its inner end and the upper end of the barrel is knurled as at 24 and preferably provided with a head 25 of relatively small diameter and also knurled. This head 25 is for the purpose of permitting quick rotation of the barrel 21 and also to provide means whereby, when the spindle 22 is approaching the anvil or approaching an object being measured, the force applied to the barrel and the spindle may be reduced by operating the barrel by means of the head 25 instead of by operating the barrel directly.

While we do not wish to be limited to the details of construction, it will be seen that the upper end of the spindle 22 is enlarged as at 26, that this is sweated into the upper end of the barrel 21 and that the head 25 is formed as part of the spindle.

The fixed barrel 15 from a point just above the

collar 14 is provided with a longitudinally extending series of graduations designated 21, the graduations indicating inches and fractions thereof, the graduations being one-sixteenth of 5 an inch apart and starting with an index point designated naught and terminating with an index mark indicating two inches though, of course, we do not wish to be limited to the length of the barrel.

10 In view of the fact that the screw-threads 20 and 23 have a pitch of sixteen to the inch, it will be obvious that a complete rotation of the barrel 21 in either direction will cause the barrel 21 with its spindle 22 to move one-sixteenth of 15 an inch, which movement is indicated by the graduations 27.

The lower end of the barrel 21, as shown in Figure 1, is provided with graduations 29 extending circumferentially around the barrel 20. There are four main graduations, one designated "0", and diametrically opposite this index or naught graduation is the graduation "32". Half way between the graduations "0" and "32" are 25 graduations numbered "64". Obviously a complete rotation of the barrel to bring the naught graduation from a point over the vertical line 28 to a point again over the vertical line 28 on the barrel 15 will mean that the barrel 21 has been rotated through a complete revolution. Equally obviously, when the barrel has been 30 rotated through a half revolution, it will have moved through a space of a thirty-second of an inch and the numeral "32" will be above the line 28. If the barrel has been moved a quarter 35 turn, one or the other of the numerals "64" will come opposite the line 28 which will indicate that the barrel and spindle have been longitudinally shifted one sixty-fourth of an inch. Intermediate the numerals "0", "32" and "64", the barrel is provided with a series of graduations 40 which are sixteen in number between each two numerals. Thus these minor divisions of scale 29 are indicated as half of a sixty-fourth, a quarter of a sixty-fourth, an eighth of a sixty-fourth and a sixteenth of a sixty-fourth.

45 The spindle 22, as shown in Figure 5, is provided with a plurality of longitudinal series of numerals capable of being read through the aperture 17, the numerals of three of the series being $\frac{1}{16}$ of an inch apart and of the other beneath the zero index being $\frac{1}{8}$ of an inch apart. These several series of numerals are disposed at 50 intervals of ninety degrees apart so that these several series of numerals come immediately beneath and in vertical alinement with the graduation numerals on the lower end of the sleeve 21.

55 In register with the index mark 0 on the barrel, the spindle carries a vertical series of numerals reading from one to fifteen and then again from one to fifteen and increasing by increments of two. Registering with the "32" mark on the barrel are a longitudinal series of numerals reading from one to thirty-one and then from one to thirty-one and increasing by increments of two. Registering with the mark "64" to the right hand 60 of the zero mark on the lower end of the barrel, are a series of numerals reading from three downward to sixty-three and then from three downward to sixty-three and increasing by increments of four. Registering with the mark "64" on the 65 left hand of the zero mark on the rotatable barrel are series of numerals starting with 1 and proceeding to 61 and then from 1 to 61 progressing by increments of four as 1, 5, 9, etc. The spaces between the numerals 0 to 32 and 64 on the barrel 70

are subdivided into sixteenths so that the rotation through one of these subdivisions will give a longitudinal movement of one-half of a sixty-fourth, a fourth of a sixty-fourth, an eighth and a sixteenth of a sixty-fourth, carrying the scale down in terms as the mechanic knows it. It will be seen that this caliper may be easily read by any mechanic in terms of those fractions of an inch with which he is entirely acquainted, as one-half, one-fourth, one-eighth, one thirty-second, and one sixty-fourth and that in use, he will read the sixteenth units on the scale 27 or he may read even graduations of scale 27 on this scale and his odd graduations through the aperture 17. The measurements of and less than one-sixteenth he 15 will read through the aperture 17 and on scale 29, reading the numerator of the fraction through the aperture 17 and the denominator on scale 29 as $5/32$ or $7/64$ or $17/64$, etc. If he wishes a dimension less or greater than the fraction indicated, he can turn the barrel a space indicated by a minor subdivision of scale 29.

20 It will be seen that all of the subdivisions of the scales used are based upon commonly used and easily understood fractions of an inch; thus the 25 scale 27 is divided into sixteen subdivisions to an inch, the screw, of course, having sixteen threads to an inch, the scale 29 is subdivided into one-half and again into one-quarter of a 16th which equals $1/32$ or $1/64$ of an inch and the scale 22 30 reads from 1 to 63 so as to measure from $1/64$ of an inch to $63/64$ of an inch while the scale 29 between "0" and "64" and between "64" and "32" is still further subdivided into sixteenths so that there are sixty-four minor subdivisions around 35 the entire scale 29. It is impossible to subdivide this scale 29 in any other way and permit the mechanic to readily read halves, quarters or eighths and sixteenths of $1/64$.

40 We claim:—

1. A direct reading speed caliper including a frame, a fixed inner barrel and an anvil carried by the frame; a rotatable, longitudinally movable outer barrel and a spindle carried thereby, the rotatable barrel extending over the fixed barrel 45 and the spindle extending through the fixed barrel; the fixed barrel and the spindle having interengaging screw-threads having a pitch of sixteen threads to the inch; the fixed barrel having a longitudinally extending index line and a longitudinally extending scale thereon reading in sixteenths of an inch; the rotatable barrel having a circumferential scale coordinated with the vertical index line and having a zero index point; a numeral indicating $1/32$ of an inch diametrically 50 opposite the zero point and two numerals indicating $1/64$ of an inch disposed 90° from and on each side of the zero point; the spindle having four longitudinal series of numerals three of these 55 series being spaced apart $1/16$ of an inch and the fourth being spaced apart $1/8$ of an inch and in alinement with the four subdivisions of the scale on the rotatable barrel and respectively coaxing therewith to indicate fractions of an inch, the numerals on the spindle which are spaced apart $1/16$ of an inch and the numerals on the rotatable barrel alined therewith indicating respectively the numerators of said fractions and the denominators thereof.

2. A caliper including a frame, a fixed barrel 70 and an anvil carried by the frame; a rotatable and longitudinally movable barrel and a spindle carried thereby, the rotatable barrel extending over the fixed barrel, and the spindle extending therethrough; the fixed barrel and the spindle 75

having engaging screw-threads having a pitch of sixteen to the inch; the fixed barrel having a longitudinally extending index line and a longitudinally extending scale thereon reading in sixteenths of an inch; the rotatable barrel having a circumferential scale co-ordinated with the vertical index line and having a zero point, a numeral indicating $\frac{1}{16}$ of an inch diametrically opposite the zero point and two numerals indicating $1/64$ of an inch disposed 90° from and on each side of the zero point, a spindle having four longitudinal series of numerals in alinement with the four subdivisions of the scale on the rotatable barrel, the numerals of three of these series being spaced apart $\frac{1}{16}$ of an inch and the remaining series having its numerals $\frac{1}{8}$ of an inch apart, said four series of numerals respectively coacting with the scale on the rotatable barrel to indicate fractions, the numerals on the spindle which are spaced apart $\frac{1}{16}$ of an inch and the numerals on the rotatable barrel alined therewith indicating respectively the numerators and the denominators of said fractions; the extremity of the barrel adjacent the anvil being formed with an aperture through which the numerals on the spindle can be successively seen as the rotatable barrel and spindle are rotated.

3. A caliper including a frame, a fixed barrel, an anvil carried by the frame, a rotatable, longitudinally movable barrel surrounding the fixed barrel, and a spindle carried by the rotatable barrel and extending through the center of the fixed barrel toward the anvil, the fixed barrel having interior screw-threads and the spindle having coacting screw-threads, the screw-threads having a certain definite unit of pitch, the fixed barrel having a longitudinally extending index line and longitudinally extending scale thereon reading in the same units as the unit of pitch of said screw, the rotatable barrel having a circumferential scale coordinated with the vertical index lines and having a zero index point, and numerals spaced equi-distantly around the barrel and indicating fractions of said unit, the spindle having a plurality of longitudinal series of numerals, the series being equal in number to the number of numerals on the rotatable barrel and the numerals of each series being spaced from each other a distance equal to the unit of measurement used for the screw-threads, the series of

numerals reading downward toward the free end of the spindle, the several series of numerals co-acting with the several subdivisions and their numerals on the rotatable barrel to indicate fractions or multiples of the unit measurement, the numerals on the spindle which are spaced apart $\frac{1}{16}$ of an inch indicating the numerators of said fractions and the numerals on the barrel alined therewith indicating the denominators of the fractions.

4. A caliper including a frame, a fixed barrel and an anvil carried by the frame; a rotatable and longitudinally movable barrel and a spindle carried thereby, the rotatable barrel extending over the fixed barrel and the spindle extending therethrough; the fixed barrel and the spindle and barrel having engaging screw-threads having a pitch of sixteen to the inch; the fixed barrel having a longitudinally extending index line and a longitudinally extending scale thereon reading in sixteenths of an inch; the rotatable barrel having a circumferential scale co-ordinated with the vertical index line and having a zero point, a numeral indicating $\frac{1}{16}$ of an inch diametrically opposite the zero point and two numerals indicating $1/64$ of an inch disposed 90° from and on each side of the zero point, the spaces between the four divisions above indicated being in turn divided to give one-half of a sixty-fourth, one fourth of a sixty-fourth, one-eighth of a sixty-fourth and one-sixteenth of a sixty-fourth, the spindle having four longitudinal series of numerals in alinement with the four main subdivisions of the scale on the rotatable barrel, the numerals of three series being spaced apart $\frac{1}{16}$ of an inch and the fourth series being $\frac{1}{8}$ of an inch apart, said four series of numerals respectively coacting with the scale on the rotatable barrel to indicate fractions, the numerals on the spindle which are spaced apart $\frac{1}{16}$ of an inch and the numerals on the rotatable barrel alined therewith indicating respectively the numerators and the denominators of said fractions; the extremity of the barrel adjacent the anvil being formed with an aperture through which the numerals on the spindle can be successively seen as the rotatable barrel and spindle are rotated.
